UNITED STATES PATENT OFFICE.

JOHANNES RUTHS, OF DJURSHOLM, SWEDEN, KARL INGERÖ, OF CHRISTIANIA, NORWAY, AND HANS SCHRENK, OF CHARLOTTENBURG, GERMANY, ASSIGNEES TO AKTIEBOLAGET VAPORACKUMULATOR, OF STOCKHOLM, SWEDEN, A CORPORATION OF SWEDEN.

PLANT WHERE HEAT-CONSUMING APPARATUS COOPERATES WITH A NUMBER OF FEED CONDUITS.

Application filed December 7, 1922. Serial No. 605,531.

To all whom it may concern:

Be it known that we, JOHANNES RUTHS, KARL INGERÖ, and HANS SCHRENK, subjects of Sweden, Norway, and Germany, respectively, residing at Djursholm, Sweden, Tordenskjoldspads 3, Christiania, Norway, and Fritschestrasse 69, Charlottenburg, Germany, respectively, have invented certain new and useful Improvements in Plants Where Heat-Consuming Apparatus Cooperate with a Number of Feed Conduits, of which the following is a specification.

In a number of plants where heat consuming apparatus is used it is often desired to feed such apparatus from different feed conduits having different conditions prevailing therein, for instance different pressures or temperatures, the apparatus being fed first from one of these conduits, as long as this is allowed by the conditions, feeding from the other conduit being resorted to only afterwards.

For example, it occurs in steam plants that digesters, drying machines or the like are to be provided with steam from two conduits having different steam pressures prevailing therein, the supply of steam taking place, for instance, first from the conduit with the lower pressure and being utilized to start the digester, a change to feeding from the other conduit with the higher pressure being effected as soon as the rising pressure of the digester has attained a value equal to that of the pressure in the first-mentioned feed conduit.

Conditions like these prevail most frequently in plants provided with heat accumulators. In such plants it may frequently occur that the condition in one of said feed conduits also varies according to the condition of charge of the accumulator. In such plants, endeavors are primarily directed to a utilization of the heat accumulated in the accumulator. When such heat is no longer sufficient, feeding from another steam conduit of higher pressure, for instance from the steam boiler conduit, is resorted to.

The consumers may be of a type wherein the condition (pressure or temperature) is apt to vary, such as digesters, as mentioned

above, or, a certain constant condition may be required for the operation of the consumers, as in drying machines or the like.

If the changes from the one to the other feed conduit are effected manually, they are frequently not carried out at the proper moments, which may result in the following inconveniences.

Assume that a digester is started with steam from a conduit of low pressure. When the pressure in the digester has attained the value of the pressure prevailing in the low pressure conduit, the shift to a conduit of higher pressure is perhaps neglected and the digester is allowed to stand for some time under a constant or even a sinking pressure, as may occur if other consumers are fed from the same conduit at the same time, in which case the sinking pressure may have a most ruinous effect on the contents of the digester.

In other instances the change is effected too soon so that steam from a conduit of lower pressure is not adequately utilized.

These changes are particularly difficult to attend to if a plurality of consumers, cooperating for instance with one another at different pressures or temperatures, are connected between the various feed conduits. If there are heat accumulators mounted in the plant, it is desirable, for their adequate utilization, that they are able to give off, entirely automatically, accumulated heat to places where conditions will permit this.

The present invention has for its object to facilitate, as far as possible, feeding of the consumer from the one of the feed conduits, and to effect an altogether automatic change to the other feed conduit, where this may be required, and the invention comprises mechanism so devised that it will then automatically cut off the connection from the consumer to the former feed conduit.

The invention will be described more fully hereinbelow, reference being had to Figs. 1 and 2 of the accompanying drawings which represent two embodiments of the invention.

In Fig. 1, the invention is shown as applied to a steam plant in which a digester *a* (sulphite- or sulphate digester) is connected are

provided between two steam conduits *b* and *c* having different pressures prevailing therein, for instance about 120 pounds per square inch in *b* and about 60 pounds in *c*.

The digester *a* is arranged for steaming processes and for indirect as well as for direct boiling. For these operations, the digester is supplied with steam through the various cut-off valves *d*, *e*, *f*. The indirect boiling is effected by admitting steam through the coiled pipe *g* provided in the digester. From the feed conduit *b*, steam may be supplied to the digester through the conduit *h* and from the feed conduit *c* through the conduit *i* which is in this case connected to the conduit *h*. Besides, there are preferably arranged two cut-off valves *k* and *l* in the conduits *h* and *i*, in the manner indicated in Fig. 1. Moreover, there is inserted in the conduit *i*, a member *x*, in this case a non-return valve, which disconnects the communication between the digester and the feed conduit *c* as soon as the pressure in the conduit *h* is greater than in the conduit *i* behind such member. Under certain circumstances it may also be advantageous to provide a similar member in the conduit *h*, which is indicated in Fig. 1 by dotted lines. Moreover, there is provided a valve member *m* in the conduit *h*, the said valve member being in the present case responsive to and actuated by the pressure of the digester and both the pressure in the conduit *c* in such a manner that, when these pressures are the same, valve *m* will open and admit steam from the conduit *h* to the digester. Through the conduits *n* and *o*, the pressures in the digester and the conduit *c* respectively are caused to act on either side of a piston *y*. If these pressures are the same, the valve *m* will be opened through the influence of the weight *p*. If the pressure in *c* is higher than in the digester, valve *m* is kept closed, but opened should the pressure in the digester be equal to or greater than in *c*. Thus, valve *m* is either entirely opened or fully closed. It may also occur, however, that the valve *m* regulates also between these two positions.

Instead of as indicated above, the pressures in the digester and the conduit *c* may actuate the valve *m* indirectly, for instance through the intermediary of a pressure liquid which, according to the variations in pressure, is caused to act on the auxiliary motor which, in turn, adjusts the valve *m*.

The plant operates in the following manner:—

Assume that the cut-off valves *k* and *l* stand open. Now, if, for instance, boiling is to take place in direct manner, the valve *f* is opened so that steam is supplied to the digester from *c* through the conduit *i*, the cut-off valve *l*, the non-return valve *x*, the conduit *h* and the cut-off valve *f*. The pis-

ton *y* is then kept in the position shown in the drawing, on account of the pressure in *c* being greater than in the digester, while the valve *m* is closed.

Now it may occur that the pressure in the conduit *c* is constantly of a certain value, in which case valve *m* opens in the manner above described on the pressure of the digester having attained this value, steam being then supplied to the digester *a* from the conduit *b*, and the digester may be started up further and the material under treatment finished with steam from the said conduit *b*. The valve member *x* (in this case a non-return valve) will then prevent steam from the conduit *b* from flowing through the conduit *i* out into the conduit *c*.

It may also occur, however, that the pressure in the feed conduit *c* varies. This is for instance the case if this conduit is connected directly to an accumulator since the pressure then varies according to the condition of charge in the accumulator. It is readily to be seen that in these cases, too, the plant operates in the manner above described. The mode of operation is the same if the digester is supplied with steam through the valves *d* and *e* for steaming purposes or for indirect boiling. If a plurality of consumers are connected to the feed conduit *c*, each of such consumers being provided with the same or similar arrangements, it will be understood that feeding from the feed conduit *c* will always take place to that consumer or those consumers wherein the pressure conditions will allow this.

Thus, if an accumulator is connected to this conduit, the latter will always discharge into the consumers in which the pressure is lower than that prevailing in the accumulator.

Fig. 2 illustrates another embodiment of the invention. In this plant there are inserted consumers *H*, *I* and *a* between the feed conduits *b* and *c*, to which latter is connected an accumulator *A* by means of two non-return valves *B*. In this case the feed conduit *b* extends from the boilers *C*. If desired, consumers *D* consisting, for instance, of steam engines, high pressure digesters or the like may also be supplied with steam from this conduit. Inserted between the conduits *b* and *c* is an over-flow valve *E*, that is to say a valve which, on a rise of the pressure before the same, admits more steam to the conduit *c*; if this steam quantity cannot, for the moment, be consumed in consumers connected to the conduit, the same is conducted to the accumulator which is then charged. If the pressure in conduit *b* would fall for some reason or other, the valve *E* decreases, or entirely cuts off the amount of steam trans-

- mitted through the same to the conduit *c*. That the over-flow valve *E* is actuated by the pressure before the same, is indicated in the figure by a line connecting the conduit before the valve with the actuating mechanism for the valve. The overflow valve in combination with the accumulator forms the subject-matter of a separate application of Johannes Karl Ruths, Serial No. 305,622 filed June 20, 1919.
- In the plant, there are also provided two conduits *F* and *G* from which two consumers *H* and *I* are supplied with steam, said consumers consisting, for example, in drying machines. Assume that constant pressures of 2 kg./sq. cm. and 1 kg./sq. cm. respectively are required before these machines for driving same. Assume further that a pressure of, for instance, 10 kg./sq. cm. prevails in the feed conduit *b* and that the pressure in the accumulator varies between 4 and 1 kg./sq. cm. according to the charge thereof. Connected to the conduit *c* is also a conduit *K* through which steam is conducted to a digester *a*, which is connected between the conduits *b* and *c* in the manner described with reference to Fig. 1, the said digester operating for instance between 0 and .8 kg./sq. cm. The reference characters of this digester with its conduits correspond to the characters used in Fig. 1. In the conduits *F* and *G* there are inserted reducing valves *P* and *Q*, and between these valves and the consumers *H* and *I* are members *x* consisting in non-return valves in this case. The lines connecting the valves with the conduits indicate that the respective valves are responsive to and actuated by the pressure in the portion of the conduit to which this line is connected. The valves *N* and *Q* are also reducing valves co-operating with valves *P* and *Q* in such a manner that the valves *N* and *O* commence to open only when the reducing valves *P* and *Q* respectively are fully opened. These valves *P* and *Q* control the amount of steam supplied from the accumulator to the consumers.
- The operation is as follows:
- Assume that for the moment there is a pressure of 2.5 kg./sq. cm. in the accumulator. Under this condition the consumers *H* and *I* operating with constant pressure receive steam from the accumulator through the reducing valves *P* and *Q* which regulate the steam quantities supplied so that the definite pressures 1 and 2 kg./sq. cm. before the respective consumers are maintained. The non-return valves *x* are then both open, whereas the reducing valves *N* and *O* are both closed. Now, if the pressure of the accumulator falls down to 2 kg./sq. cm. by reason of the discharge, the valve *Q* becomes fully open; if the pressure falls further, the reducing valve *O* opens and supplies steam to the consumer *I* from the feed conduit *b*. The non-return valve *x* which is now closed by the steam pressure prevents steam from flowing from the conduit *b* out into the conduit *c* through the open valve *Q*.
- If the pressure of the accumulator falls further on account of a further discharge, for instance below 1 kg./sq. cm. the valve *N* opens and admits steam to the consumer *H*, the non-return valve *x* arranged in conduit *F* then preventing the steam supplied through the valve *N* from flowing out into the conduit *c*.
- The operation of the arrangement with respect to the consumer (or consumers) *a* provided in the plant should be easily understood from the description with reference to Fig. 1. In addition to the consumers mentioned herein, it is evident that other such consumers may receive their steam from the accumulator, such consumers consisting for instance of radiators *R* for heating purposes, steam engines and so forth. Obviously, it is not necessary that the feed conduit *b* extends directly from the boilers. Between this conduit and the boilers there may for instance be arranged other steam consumers such as steam engines or the like.
- It will be understood from the above that the steam accumulated in the accumulator will be utilized in a most rational manner, by means of the invention set forth, in that a discharge may take place entirely automatically to the consumers where the pressure conditions will allow this.
- Similar conditions are to be found in such industries, for example the textile industry, where hot water storers are often preferably arranged in place of steam storers, and where the heat is supplied to the consumers in the form of hot water. Instead of pressure controls, temperature regulators may be used.
- What we claim as new and desire to secure by Letters Patent of the United States is:
1. In combination, a digester, a high pressure conduit adapted to supply steam to said digester, a low pressure conduit adapted to supply steam to said digester, and automatic means to control the flow of steam from said high pressure conduit to said digester responsive to conditions in the digester and conditions in the low pressure conduit.
  2. In combination, a digester, a high pressure conduit adapted to supply steam to said digester, a low pressure conduit adapted to supply steam to said digester, and automatic means to control the flow of steam from said high pressure conduit to said digester responsive to the pressure in said digester and responsive to the pressure in the low pressure conduit.

3. In combination, a digester, a high pressure conduit adapted to supply steam to said digester, a low pressure conduit adapted to supply steam to said digester, and 5 automatic means to control the flow of steam from said high pressure conduit to said digester responsive to conditions in the digester and conditions in the low pressure conduit and a non-return valve to control the flow of steam from said low pressure conduit to the digester.
4. In combination, a digester, a high pressure conduit adapted to supply steam to said digester, a low pressure conduit adapted to 15 supply steam to said digester, and automatic means to cut off the supply of steam from the low pressure conduit and admit steam to the digester from the high pressure conduit when the pressure in the digester exceeds the pressure in the low pressure conduit.
5. In combination, a digester, a high pressure conduit, a low pressure conduit, a third conduit connecting said high pressure conduit with said digester, a fourth conduit connecting said low pressure conduit with said digester, a valve in said third conduit, means operating to open said valve when the pressure in the digester exceeds the pressure in the low pressure conduit, and means in said fourth conduit to prevent flow of steam from the digester to the low pressure conduit when the pressure in the digester exceeds the pressure in the low pressure conduit.
6. In combination, a digester, a high pressure conduit, a low pressure conduit, a third conduit connecting said high pressure conduit with said digester, a fourth conduit 40 connecting said low pressure conduit with said digester, a valve in said third conduit, means operating to open said valve when the pressure in the digester exceeds the pressure in the low pressure conduit, and a non-return valve in said fourth conduit.
7. In combination, a digester, a high pressure conduit, a low pressure conduit, a third conduit connecting said high pressure conduit with said digester, a fourth conduit 50 connecting said low pressure conduit with said digester, a valve in said third conduit, means responsive to the pressure in the digester and the pressure in the low pressure conduit operating to open said valve when the pressure in the digester exceeds the pressure in the low pressure conduit, and means in said fourth conduit to prevent flow of steam from the digester to the low pressure conduit when the pressure in the digester exceeds the pressure in the low pressure conduit.
8. In combination, a digester, a high pressure conduit, a low pressure conduit, a third conduit connecting said high pressure conduit with said digester, a fourth conduit 60 connecting said low pressure conduit with said digester, a valve in said third conduit, means to operate said valve responsive to the pressure in the digester and the pressure in the low pressure conduit when the pressure in the digester exceeds the pressure in the low pressure conduit.
9. In combination, a steam consumer, a high pressure conduit adapted to supply steam to said steam consumer, a low pressure conduit adapted to supply steam to the steam consumer, and automatic means to cut off the supply of steam from the low pressure conduit and admit steam to the steam consumer from the high pressure conduit when the pressure in the steam consumer exceeds the pressure in the low pressure conduit.
10. In combination, a steam consumer, a high pressure conduit, a low pressure conduit, a third conduit connecting said high pressure conduit with said steam consumer, a fourth conduit connecting said low pressure conduit with said steam consumer, a valve in said third conduit, means operating to open said valve when the pressure in the consumer exceeds the pressure in the low pressure conduit, and means in said fourth conduit to prevent flow of steam from the steam consumer to the low pressure conduit when the pressure in the steam consumer exceeds the pressure in the low pressure conduit.
11. In combination, a consumer, a conduit carrying a medium of high thermal condition adapted to supply said medium to said consumer, a conduit carrying a medium of low thermal condition adapted to supply said medium to said consumer, automatic means to cut off the flow of medium from the second mentioned conduit to the consumer and means to increase the flow of medium from the other conduit dependent on the relative thermal conditions prevailing in the consumer and in the conduit of low thermal condition.
12. In combination, a consumer, a conduit carrying a medium of high thermal condition, a second conduit carrying a medium of low thermal condition, a third conduit connecting said first-mentioned conduit with said consumer, a fourth conduit connecting said second conduit with said consumer, a valve in said third conduit, automatic means to operate said valve responsive to the relative thermal conditions prevailing in said consumer and in said second conduit, and a non-return valve in said fourth conduit.
13. In a steam plant, a high pressure conduit, a low pressure conduit, a consumer adapted to operate at a predetermined pres-

sure, means to supply steam to said consumer from said low pressure conduit when the pressure in the low pressure conduit is greater than said predetermined value and to automatically cut off connection between said low pressure conduit and said consumer when the pressure in the low pressure conduit falls below said predetermined pressure, and means to supply steam to said consumer from said high pressure conduit when the connection between said low pressure conduit and said consumer is cut off.

14. In a steam plant, a consumer, a high pressure conduit, a low pressure conduit, a third conduit connecting said high pressure conduit with said consumer, a fourth conduit connecting said low pressure conduit with said consumer, a reducing valve in said fourth conduit, a non-return valve in said fourth conduit, a reducing valve in said third conduit, the reducing valves being responsive to the pressure of the consumer and so set that the reducing valve in the third conduit opens when the pressure actuating the reducing valves has fallen below the value at which the reducing valve in the fourth conduit is fully open.

15. In a steam plant, driers, a high pressure conduit, a low pressure conduit, an accumulator connected to the low pressure conduit, means to lead steam from said conduits to said driers, and automatic means

to control the flow of steam from the respective conduits to the driers in proportion to the relative pressure in the accumulator and the pressure at which the driers operate.

16. In a steam plant, a high pressure conduit, a low pressure conduit, driers, a third conduit connecting said high pressure conduit with said dryers, a fourth conduit connecting said low pressure conduit with said dryers, a valve in said third conduit, a valve in said fourth conduit, means to operate said valves responsive to the pressure in conduits immediately connected with the driers, said means operating to maintain the valve in the third conduit closed and to actuate the valve in the fourth conduit to throttle the steam flowing therethrough when the pressure in the low pressure conduit is above a predetermined value and to open the valve in the third conduit and throttle the steam flow therethrough when the pressure in the low pressure conduit falls below said predetermined value and means to prevent steam from flowing through the valve in the fourth conduit toward the low pressure line when the valve in the third conduit is open.

In testimony whereof we affix our signatures.

JOHANNES RUTHS.
KARL INGERÖ.
HANS SCHRENK.
